UNITED STATES PATENT OFFICE.

RICHARD R. MOFFATT AND SYLVESTER CHICHESTER, OF BROOKLYN, N. Y.

ELECTRIC LAMP.

SPECIFICATION forming part of Letters Patent No. 245,309, dated August 9, 1881.

Application filed March 21, 1881. (No model.)

To all whom it may concern:

Be it known that we, RICHARD R. MOFFATT and SYLVESTER CHICHESTER, both of the city of Brooklyn, in the county of Kings and State of New York, have invented certain Improvements in Electric Lamps; and we do hereby declare the following to be a full, clear, and exact description of the invention, such as will enable others skilled in the art to which it pertains to make and use it, reference being made to the accompanying drawings, which form part of this specification.

Our invention relates to devices for regulating the distance between the points of the electrodes in what is termed a "point-to-point electric lamp;" and it consists in a novel arrangement of electro-magnets located in the main circuit combined with electro-magnets located in a shunt or derived circuit in such a manner that the slightest change in the resistance of the arc will cause the electro-magnets to operate mechanism which will produce a sufficient feed movement of the electrodes as they are consumed, to keep them always at the proper distance apart for the production of light of a maximum intensity.

In the drawings, Figure 1 is a front elevation of a device embodying our invention, the lower portion of which is shown partly in section. Fig. 2 represents a plan of the upper part of the same. Fig. 3 represents a plan view of the upper part of the same with the electro-magnets removed, and showing the tilting armature in position. Fig. 4 is a side view, showing the tilting armature in position. Fig. 5 is a sectional view of the carbon holder and tube, illustrating the manner of its operation.

Similar letters of reference in the several figures indicate like parts.

In the drawings, A is a plate of wood, which, with the metal pieces a a and a' a', form the frame of the lamp.

B is an electro-magnet, which is provided with a hollow core, within which is located a carbon-holder rod c. On the upper end of the rod c is secured the iron armature B'. The rod c is capable of a longitudinal movement within the magnet B. A set-screw nut, d, working near the lower extremity of the rod

c, regulates the movement of the rod, and a small spiral spring, e, tends to force the rod c upward when the electric circuit is broken. The armature B' moves with the rod, and when the electric circuit is complete the magnet B will draw the armature B', the lower carbon, and the rod downward, thus separating the points of the electrodes to form the arc.

M is an electro-magnet, which is secured to one arm of a yoke, h, the latter being secured to a metallic tube, F. On the other arm of the yoke h is mounted an electro-magnet, N. This magnet is so arranged that it can be adjusted by means of a screw-rod, i, and the two screw-nuts i'. The armatures of these electro-magnets M and N are firmly secured together by a non-magnetic material, and are pivoted to standards g g, as shown in Figs. 3 and 4, in such a manner that the armatures k and k' will each be influenced by the magnetic force of both the electro-magnets M and N. These magnets are so wound (or connected up) with wire that the electric current passing in them will cause the poles to be of like nature in each bobbin or helix that faces (and acts upon) the same armature. For example, the armature k will have the north pole of the magnet M acting upon one end and the north pole of the magnet N acting upon its other end, while the same effect takes place with the south poles of the magnets M and N upon the armature k'. The magnet M is placed in the main circuit, which conveys the electric current through the arc, and the magnet N, which is made of fine insulated wire having comparatively great resistance, is located in a shunt or derived circuit.

p is a tube the lower end of which carries a carbon-holder. This tube is arranged to move within the large tube F, in the upper part of which are located small pulleys.

W is a weight, to which cords or chains are attached, which, extending upward and over the pulleys, are made fast to the tube p. The weight W tends to counterbalance the weight of the tube p, the latter having a slight preponderance, thus causing it to move slowly downward by its gravity. The tube F is secured at its lower end to the plate A, as shown in Fig. 5.

A lever-brake, *s*, is located as shown, one end of which rests against the tube *p*. A rod, *s'*, extends from the lever to the armature-frame. Each end of the rod enters a recess, 5 which keeps it in position.

t is a set-screw for adjusting the movement of the tilting armature.

The operation of our invention is as follows: When the electric circuit is made the current 10 enters the binding-post +, through the magnet *M*, into the yoke and tubes *F* and *p*; thence through the carbons, the magnet *B*, and frame to the binding-post - in its passage. Thus it causes the magnet *M* to attract the tilting 15 armatures *k* *k'*, raising the ends nearest to the magnet *M* and causing the other ends to be depressed, which, in turn, presses upon the rod *s'* and lever *s*, thereby preventing the movement of the tube *p*, (and the carbon at- 20 tached thereto.) At the same time the armature *B'* is drawn down by the magnet *B*, taking with it the lower carbon, thus separating the electrodes, when the arc will appear. A portion of the current passes from the binding- 25 post marked +, through the magnet *N*, to the binding-post marked -, (said magnet *N* having high resistance, as described.) As the carbons are consumed the size of the arc in- 30 creases, and with it the resistance to the elec- tric current increases, and the attractive force 35 of the magnet *M* is lessened. At the same time the magnetic power of the magnet *N* is increased in proportion to the increase of re- sistance in the arc, and its action on the arma- 40 ture is to charge the extreme end thereof—viz., the end of the armature that is in close prox- imity to the poles of the magnet *M*—with mag- netism of a like or similar nature, thus causing the action of repulsion, which tends to force 45 the tilting armature down upon the end of the set-screw *t*, and raising the other end of the armature from the rod *s'*, thus relieving the pressure of the lever-brake *s* upon the tube *p*, when the latter moves downward by its grav- 50 ity until the distance between the carbon points is lessened, and the resistance in the electric circuit is also decreased when the mag- netic force of the magnet *M* is increased and that of the magnet *N* is decreased, thus chang- 55 ing the preponderance of like polarity in the armature to the other end thereof, and its ac- tion of repulsion upon the magnets is reversed, again depressing the armature upon the rod *s'*, lever *s*, and tube *p*, holding the latter from 60 moving. This action of the magnets *M* and *N* upon the armature, acting upon the principle of similar poles repelling each other, is so sen- 65 sitive in its action through the agency of the tilting armature, (the movement of which is so slight,) as described, that the feeding of the carbons and the size and resistance in the arc are regulated automatically with the best results for the production of light of a maximum in- 70 tensity.

65 By means of screw-nuts *i i* the resistant-

magnet *N* may be adjusted by increasing or decreasing its distance from the armature, so as to keep any desired arc.

This arrangement of magnets and tilting armature for operating and regulating the 70 working of an electric lamp may be modified in its various details without departing from its general principles; and we do not limit ourselves to the repulsive properties of the magnets *M* and *N*, acting upon and by means 75 of an armature, for the purpose specified, as the properties of attraction as well as repul- 80 sion can be successfully utilized for the same end by simply mounting or arranging the tilting armature upon its pivots in such a man- 85 nner that the armature *k* will be under both poles of one magnet and the other armature under the poles of the other magnet. For this purpose we have shown in Figs. 3 and 4 provisions *m*, in which the pivots that sup- 90 port the tilting armature may be inserted to operate. In this case the armatures *k* and *k'* will occupy a position parallel with the central line of the pivots and at right angles to that shown in the drawings, while the posi- 95 tion of the magnets *M* and *N* will not be changed.

If desired, the weight *W* may be a tube, and made to occupy a space between the tubes *F* and *p*, the latter passing through the tube- 95 weight.

By the use of a chain-connection between the tube *p* and the counter-weight *W* said chain in its entirety being of a less weight than the carbon, an element of compensation 100 enters into the operation, which causes the preponderance in the tube *p* and carbon to be nearly the same, notwithstanding the loss of weight by the consumption of the carbon. This is caused by the weight of chain gradu- 105 ally decreasing on one side of the pulleys and increasing the weight on the other side, thus compensating for the loss in carbon by con- sumption.

The magnets *M* and *N* may be axial mag- 110 nets with movable iron cores.

Having thus fully described the nature, con- 115 struction, and operation of our invention, what we claim as new, and desire to secure by Letters Patent, is—

1. In an electric lamp, the combination of the electro-magnets *B* and *M*, located in the main circuit, and the electro-magnet *N*, located in a shunt-circuit, for the purpose of forming and regulating the arc, substantially as herein 120 specified.

2. In an electric lamp, the combination of the electro-magnets *M* and *N*, the tilting arma- 125 ture *K*, *k'* the carbon-rod *p*, and mechanism to check and regulate the feed of the carbon, sub- stantially as herein specified.

3. In an electric lamp, the combination of the electro-magnet *M*, located in the main cir- 130 cuit, and the electro-magnet *N*, located in a shunt-circuit, said magnets having poles of

like nature acting upon the same armature, substantially as and for the purpose specified. feed of the carbon, substantially as herein specified.

4. In an electric lamp, the combination of the electro-magnets M and N, the tilting armature $k k'$, the carbon-rod p , and the lever-brakes, constructed substantially as described, so that the action of magnetic attraction and repulsion will act to check and regulate the
